UNITED STATES PATENT OFFICE.

JOSEPH L. ANDERSON, OF TEXAS, MARYLAND.

HEATER AND MUFFLER.

1,200,688.

Specification of Letters Patent. Patented Oct. 10, 1916.

Application filed April 12, 1916. Serial No. 90,613.

To all whom it may concern:

Be it known that I, JOSEPH L. ANDERSON, a citizen of the United States, residing at Texas, county of Baltimore, and State of Maryland, have invented certain new and useful Improvements in Heaters and Mufflers, of which the following is a specification.

The present invention has for its object 10 the provision of improvements on the heater and muffler of my Patent No. 1,173,403, dated February 29, 1916, among which are, first, to construct the shell or body and the partitions so that the exhaust gases will be 15 choked down as they approach the exhaust or delivery port or outlet of the heater to obtain from them a maximum heat value; second, to connect the partitions to the shell and provide removable walls for either the 20 ends or sides of the shell, thus affording a tight construction with adaptability for easy cleaning, without removing the partitions, on taking off the removable walls; third, the provision of fresh air inlet ports 25 in the walls of the shell to admit air to the heat chamber and cause a free passing off of the heat which is radiated into said chamber from the interior of the shell, thus insuring adequate delivery of heat to the 30 vehicle; fourth, to provide a valve control for the admission of the exhaust gases to the heater in connection with a novel operating device therefor which is normally disposed below or flush with the floor of the 35 car and interposes no obstruction, but may be readily manipulated to open or close the valve; fifth, to generally improve the construction of the heater and muffler of my aforesaid patent.

40 The invention consists of means, instrumentalities, devices and combinations adapted to carry out the foregoing objects.

The embodiments of the invention which are hereinafter described and shown in the 45 accompanying drawings are to be considered as illustrative, rather than restrictive, of the scope of the invention, as the principle thereof may be embodied in modified constructions.

50 In the accompanying drawings: Figure 1 is a detail vertical section with parts broken away, taken on line 1—1, Fig. 3, showing the invention and the controlling means therefor; Fig. 2, a longitudinal section through the heater and muffler; Fig. 3, a front elevation; Fig. 4, a detail of another

form of valve which may be used; Fig. 5, a perspective showing the invention in use on an automobile, a portion of which is shown; and Fig. 6, a detail of one of the 60 fastening bolts and parts of the heater and muffler connected thereby.

The body or shell 1 of the heater or muffler may be of cast iron or sheet metal, preferably the latter, and provided with longitudinally extending outstanding flanges 2 and similar end flanges 3. The partition 4 which defines, in connection with the perforated register or top plate 5, the heat chamber 6, is of dish-like or pan-shaped 70 form, being provided with longitudinal side flanges 7 and end flanges 8 which lie underneath the plate 5 and are welded or otherwise tightly connected to it to prevent the exhaust from having access either to the 75 compartment 6 or the interior of the automobile. Bolts 9 connect the flanges of partition 4 and the plate 5 to the shell. The removable end walls 10 are provided with flanges 11 at their upper edges which are 80 connected by certain of the bolts 9 to the end flanges 8 and the top plate 5. The removable end walls 10 are also bolted to the end flanges 3. Asbestos facings or sheets 12 are interposed between the end walls 10 85 and the interior of the shell 1 and also between the flanges previously described so that joints are provided which will not permit the passage of the heat at these 90 points.

The partitions 13, of which there may be as many or as few as desired, are provided with longitudinal flanges 14 which may be spot-welded, riveted, or otherwise connected to the sides of the shell 1 so that they will 95 be permanently attached thereto. At their ends, these partitions are preferably provided with narrow flanges 15 so that they will form a tight joint with the asbestos sheets 12. The partitions 13 are spaced relatively close together, the intermediate compartments or chambers therebetween being shown at 16. The chamber 17 between the uppermost partition 13 and the partition 4, is of considerably greater depth than the compartments 16. The inlet for the exhaust gases, as shown at 18, admits such gases to the compartment 17, where the greatest heating effect and radiation will occur through the partition 4 into the heat chamber 6 and thence through the perforations 111 or openings 5^a in the plate 5. The gases en-

tering at one end of the heater, travel to the opposite end portion thereof before diving through one or more openings 19 in the uppermost partition 13, thence passing in 5 the opposite direction through the uppermost compartment 16 and diving through one or more openings 20 in the next lower partition 13, and then back in the opposite direction through the compartment 16 there- 10 below and so on, according to the number of partitions 13 employed, until the exhaust gases finally pass out through the opening 21 into any suitable exhaust nozzle or pipe 22. By providing a relatively large compartment 17 a maximum radiation of heat 15 from the exhaust gases is obtained when they enter the heater and muffler, and by providing relatively shallow compartments 16, which may or may not be of the same depth as each other, the gases are choked down so that the rapidity of their travel is diminished and they are retained in the heater and muffler a sufficient period to obtain from them a maximum portion of the 20 heat remaining therein, which is then radiated through the compartment 17 into the compartment or chamber 6 and out through the openings 5^a in the register plate. The choking down of the gases enables me to obtain 25 a maximum heat radiation or value from the exhaust gases, and as I am aware that this can be accomplished in various ways, I do not limit myself to the precise arrangement of partitions and chambers to 30 accomplish that end, except where so specified in the claims.

The ports or inlet openings 23 which are provided in the front face of the shell 1, are positioned to admit fresh air from the front 40 of the car into the heat chamber 6 to afford a draft or circulation which will insure the carrying off, through the openings 5^a, of the heat in the chamber 6. By providing these 45 openings 23, I am enabled to prevent heat in the chamber 6 from becoming "dead" and the heating effect is considerably enhanced.

The inlet pipe 18 is connected to the usual exhaust pipe 24 and preferably has a branch 50 thereof, the exhaust pipe, continued toward the rear of the automobile, as indicated at 24^a. The branch pipe 25 which connects pipe 24 to the inlet 18, is provided with either a rotary valve 26, as shown in Fig. 1, 55 or a butterfly damper 27, as in Fig. 4. Other forms of valves could be used.

Referring first to Fig. 1, the stem 28 of the valve 26 carries a loose, vertically slideable sleeve 29 which has a collar 30 at its 60 lower end, and at its upper end is provided with a button or finger-hold 31. Intermediate the collar 30 and the finger-hold 31 the sleeve has a longitudinally extending slot 32. The stem 28 is provided with a pin 33 which 65 is loosely received in the slot 32. The floor

of the automobile is shown at 34. Countersunk therein is a flanged bushing 35, between whose lower face and the collar 30 is interposed a coil spring 36 which holds the sleeve 29 pressed downwardly, and retracts the 70 finger-hold or button 31 into the bushing or cup 35 so that it is below, or at least, flush with the upper surface of the floor 34 and consequently no obstruction is offered which would cause occupants of the vehicle to trip. 75

In Fig. 4, the damper valve 27 has a stem 27^a provided with a pin 27^b. The operating finger-hold or button 31^a has a slot 32^a which receives the pin 27^b. The finger-hold or handle 31^a can be raised or lowered in the 80 same manner as with the operating device of Fig. 1 and if desired, spring means may be employed to hold the finger-hold 31^a in depressed position. The finger-hold 31^a may be adapted to enter a cup or bushing 85 such as shown at 35 in Fig. 1 so that it will be flush with the floor of the vehicle.

Normally the handle or finger-hold 31 is retracted into the cup 35 and when it is desired to open or close the valve 26, the finger-hold or handle 31 is grasped and pulled outwardly for purposes of manipulation. On the release of said finger-hold, the spring snaps it back into the cup or bushing 35. 90

The valve 26 being open to the desired 95 extent to admit such portion of the gases as may be needed to afford the requisite heat, the gases pass into the compartment 17 immediately underneath the partition 4 and the heat of said gases is directly transmitted to the heat chamber or compartment 100 6 and thence pass through the openings 5^a. The draft of air through the ports 23 causes the heat to be rapidly taken off through the 105 openings 5^a. Passing the length of the compartment 17, the gases dive down through the openings 19 and thence return in the opposite direction through the upper compartment 16, thence passing through the 110 openings 20 and into the lower compartment 16, whence they pass to the exhaust or outlet 22. As previously described, the choking down of the rate of travel of the 115 exhaust gases by virtue of the relative shallowness of the compartments 16, causes the gases to be retained for a sufficient length of time in the compartments to relieve them of the greater portion of their heat, which is thus transmitted to the chamber 6, by radiation, and thence through the openings 5^a to 120 the car.

When it is desired to clean the deposits from the interior of the heater, the end walls 10 are removed, whereupon the shell or body 1 and the partitions 13 which are connected thereto, may be cleaned from end to end. Instead of having the end walls 10 removable, the sides could be removable and the end walls fixed. 125

The upper face of the cup or bushing 35 130

may be provided with graduations and indicia to indicate positions of the finger-hold 31 representing "full" heat; "half" heat, etc.

5 Having thus described my invention, what I claim as new and desire to secure by Letters Patent, is:—

1. A heater and muffler comprising a flanged body or shell, a pan-shaped partition within the body or shell which defines a heat chamber adjacent said top or radiating plate, said partition having a flange overlapping the flange on the body, a removable top or radiating plate secured to 15 the flange of the pan-shaped partition and to the body one or more additional partitions defining compartments in said body or shell, there being provided means for communication between said last-named compartments, the aforesaid partitions being permanently secured to the walls of the body or shell, means for admitting a heating medium to one of the compartments and taking it off from another compartment, and other walls removably secured to 25 said body or shell and adapted to be taken off, for purposes of cleaning the heater and muffler, without disturbing the arrangement of the partitions.

30 2. A self-contained, unitary heater and muffler comprising a body or shell having a top plate and a plurality of compartments of different sizes, in communication with each other, means for admitting a heating medium to a larger one of the compartments, means for taking off the heating medium from a smaller compartment, said compartments being adapted to choke down the flow or travel of the heating medium, 35 and a partition defining a heat compartment in connection with the top plate, said compartment being sealed from communication with the remainder of the body or shell.

40 3. A self-contained, unitary heater or muffler comprising a body or shell having a top plate and a plurality of compartments of different sizes, said compartments being in communication, means for admitting a heating medium to the largest of said compartments, and for taking off said heating

medium from the smallest of said compartments, whereby the flow or travel of the heating medium is choked down from its point of entry to its point of exit from the heater or muffler, and a partition defining a 55 heat compartment in connection with the top plate, said compartment being sealed from communication with the remainder of the body or shell.

4. A self-contained, unitary heater or 60 muffler comprising a body or shell having an apertured top plate, a partition defining a heat compartment in connection with said top plate which is sealed from communication with the remainder of the body or shell, 65 one or more additional partitions defining two or more compartments of different sizes in the body or shell, the largest one of which is located adjacent the partition first-named, means for admitting a heating 70 medium to the large compartment, and means for taking off the heating medium from a smaller compartment, said compartments being in communication, whereby the flow or travel of the heating medium is 75 choked-down from its point of entry to its point of exit from the heater or muffler.

5. A self-contained, unitary heater or muffler comprising a body or shell having an apertured top plate, a partition defining a 80 heat compartment in connection with said top plate which is sealed from communication with the remainder of the body or shell, one or more additional partitions defining two or more compartments of different sizes 85 in the body or shell, the largest one of which is located adjacent the partition first-named, means for admitting a heating medium to the large compartment, and means for taking off the heating medium from a smaller 90 compartment, said compartments being in communication, the body or shell being provided with means for the admission of outside air into the heat compartment for the purpose of causing draft or circulation 95 therethrough and through the top plate.

In testimony whereof, I hereunto affix my signature.
